Primary Examiner — Xavier Marti-Santos

(57) **CLAIM**

The ornamental design for a folding mirror as shown and described.

DESCRIPTION

1. Folding mirror

1.1 : Front

1.2 : Back

1.3 : Left

1.4 : Right

1.5 : Top

1.6 : Bottom

1.7 : Perspective

1.8 : Perspective

1.1 is a front view of a folding mirror, showing my new design;

1.2 is a back view thereof;

1.3 is a left side view thereof;

1.4 is a right side view thereof;

1.5 is a top plan view thereof;

1.6 is a bottom plan view thereof;

1.7 is a perspective view thereof; and

1.8 is an alternate perspective view thereof, shown in a folded state.

1 Claim, 8 Drawing Sheets
